DESIGN FOR A COMBINED LIGHT BRACKET AND SHADE

John W. Brooks, Syracuse, N. Y., assignor to
Pass & Seymour, Inc., Syracuse, N. Y., a cor-
poration of New York

Application January 18, 1939, Serial No. 82,421

Term of patent 7 years

To whom it may concern:

Be it known that I, John W. Brooks, a citizen of the United States and resident of Syracuse, county of Onondaga, and State of New York, have invented a new, original, and ornamental Design for Combined Light Bracket and Shade, of which the following is a specification, reference being had to the accompanying drawing, forming a part thereof, and in which:

Figure 1 is a side elevation of a combined light bracket and shade showing my new design;

Figure 2 is a front elevation thereof;
Figure 3 is a top plan view thereof; and
Figure 4 is a bottom plan view thereof, all views being taken in accordance with the usual mounting position of the bracket.

I claim:

The ornamental design for a combined light bracket and shade, substantially as shown.

JOHN W. BROOKS.
